(57) **CLAIM**

The ornamental design for a surgical cutting tool, as shown and described.

DESCRIPTION

FIG. 1 is a top front perspective view of the surgical cutting tool of the present invention;

FIG. 2 is a left front perspective view thereof;

FIG. 3 is a top rear perspective view thereof;

FIG. 4 is a front view thereof;

FIG. 5 is a rear view thereof;

FIG. 6 is a left side view thereof, the right side view being a mirror image thereof;

FIG. 7 is a top view thereof, the bottom view being a mirror image thereof;

FIG. 8 is a partial top view thereof, illustrating the cutting end of the surgical cutting tool; and,

FIG. 9 is a partial bottom view thereof, illustrating the cutting end of the surgical cutting tool.

The broken lines shown in FIGS. 1-3 and FIGS. 6-7 illustrate portions of the surgical cutting tool that form no part of the claimed design. The broken line break lines shown in FIGS. 1-3 and FIGS. 6-7 illustrate a symbolic break in length and form no part of the claimed design. The appearance of any portion of the article between the break lines forms no part of the claimed design.
